UNITED STATES PATENT OFFICE.

MORRIS SCHOENFELD, OF ZURICH, SWITZERLAND.

APPARATUS AND METHOD OF WET TREATING TEXTILE THREADS.

Application filed November 21, 1928, Serial No. 321,025, and in Switzerland January 16, 1928.

This invention relates to the art of winding and wet-treating textile threads, and the invention specifically considered, involves winding the thread on a spool constructed with radially movable parts to change its diameter, the diameter being greatest for winding the thread and thereafter diminished for decreasing the tension in the wound-up goods, the latter, together with the spool forming one closed unit so that after closing the ends of the spool the treatment liquid supplied from inside or outside can only pass through the wound-up goods.

It is the object of the invention to prevent the liquid used in the wet treatment from flowing at the side of the wound up goods through the convex surface of the spool so that the consumption of the treatment liquid is decreased to the least possible amount.

The invention consists in whatever is described by or is included within the terms or scope of the appended claims.

In the accompanying drawing:

Fig. 1 shows in cross-section one embodiment of my invention with the longitudinal diameter-changing parts moved inwardly;

Fig. 2 is partly an elevation and partly a longitudinal section of the spool;

Fig. 3 shows in cross-section a second embodiment with the longitudinal diameter-changing parts moved inwardly;

Fig. 4 shows an end portion of this spool partly in elevation and partly in a longitudinal section;

Figs. 5 and 6 are views similar to Figs. 3 and 4 of the invention, in another embodiment;

Fig. 7 is a view in cross-section of a fourth embodiment with its longitudinal parts moved inwardly;

Fig. 8 is a view of this spool with parts shown in longitudinal section, and parts in elevation;

Fig. 9 is a section corresponding to that of Fig. 7, the longitudinal parts being moved outwardly;

Figs. 10 and 11 are views similar to Figs. 1 and 2 of a fifth embodiment of the invention;

Fig. 12 shows the unit in the liquid receptacle.

The spool according to Figs. 1 and 2 comprises a stationary part in the shape of a cylindrical cover 1, having longitudinal slots 2, arranged on its circumference, which, according to the drawing, are covered by longitudinal parts 3, shaped as segments in cross-section. These longitudinal parts, 3, which are guided to be radially displaceable by means of pins 4, passing through holes in the convex surface, 1, are provided in the range of the longitudinal slots 2, with a row of apertures 5, arranged in the axial direction of the spool, which apertures permit the passage of the liquid from and to the threads wound on the spool. The wound up goods A project in the longitudinal direction of the spool somewhat beyond the extent of the row of apertures 5 and of the longitudinal slots 2, respectively, so that liquid, which is supplied in the outward or inward direction to the wound up goods A, cannot escape at the end parts of the spool, where it would pass unused, but is forced to flow through the goods A. In their inwardly moved position the longitudinal parts, 3, occupying larger areas of the convex surface of the spool, rest on the stationary part 1, of the spool whereby the circular circumferential line of the spool is interrupted from one longitudinal part to the other longitudinal part. With this construction, larger areas of the convex surface of the spool are movably arranged outside of the stationary part of the convex surface of the spool.

When the thread A is being wound on the spool the longitudinal parts 3, are in their outermost position in which they are, for instance, secured by a mandrel on which the spool is pushed and on which the heads of the pins 4, rest. Afterwards, tension in the wound up threads is reduced by inwardly moving the longitudinal parts, 3, of the spool in order to be subjected to the wet-treatment.

The spool according to Figs. 3 and 4, differs from that described above inasmuch as depressions 6, are pressed into the cover 1, in which depressions the longitudinal parts 3, are housed so that the latter together with the stationary cover of the spool form a circular circumferential line or a closed convex

surface respectively; thereby a very favorable bearing surface is provided for the loosened wound-up goods. With this construction, one row of apertures 7, is provided 5 in the stationary part 1, of the spool between every two depressions 6.

The spool as shown in Figs. 5 and 6 differs from the foregoing example inasmuch as the depressions are solely formed by tongue parts 10 pressed into the stationary part 1, of the spool, which tongues limit the ends of longitudinal slots 2, provided in the cover 1, of the spool.

In the construction illustrated in Figs. 7-9, 15 the spool is provided with ring-shaped end parts 1, rigidly connected to each other by four bars, 8. In the stationary part 1, of the spool the segment-shaped longitudinal parts 3, are radially displaceable and guided by 20 the pins 4, provided with heads, which longitudinal parts form a closed convex surface, an extension 3' provided on the longitudinal edge of a single longitudinal part 3, projecting below the adjacent longitudinal part 3. 25 And when the longitudinal parts 3 are moved into their outermost position the convex surface is continuous, as is shown in Fig. 9. The longitudinal parts 3 are provided with two rows of apertures, 5.

30 The spool illustrated in Figs. 10 and 11 is provided at its ends with ring-shaped parts 1, rigidly connected to each other by means of bars, 9. In the latter longitudinal parts 3, are radially displaceable and guided by 35 pins 4 provided with heads. The longitudinal parts 3 form a ring-shaped convex surface provided with longitudinal slots 10. The longitudinal parts 3 are each provided with two rows of apertures 5.

40 When the thread A is wound on the spool the longitudinal parts of the latter are on their outermost position in which they are secured, for instance, by a mandrel on which the spool is pushed and against which the heads of the pins bear. Also with the longitudinal parts in their outermost position these parts form a closed continuous convex surface as is shown in Fig. 9, for example.

The wound-up goods A formed, for instance, of artificial silk, extend somewhat further in the longitudinal direction of the spool than the rows of apertures 5, or beyond the inner edge of the end parts 1, respectively, so that liquid supplied from outside or inside the spool to the wound-up goods A flows substantially through these goods and does not escape at the ends of the spool.

45 After the thread A has been wound on the spool the longitudinal parts 3 of the latter are moved inwardly. The wound-up goods form together with the spool one closed unit, as the wound-up threads are still under sufficient tension to maintain their position on the spool. In this state the spool according

to Fig. 12 is vertically placed into the liquid receptacle 12, one end part 1, being inserted in the flange 13, of a lower supporting member 14, whilst over the upper end part of the spool a cover disc 16, provided with a flange 15, is placed. The cover disc 16 is slidably mounted on a conduit 18 supplying the liquid and is urged against the spool by a compression spring 17. The receptacle 12, is provided with an emptying conduit 20, in which a cock, 19 is inserted and with a discharge conduit 23, having a cock 22, and leading to a suction pump 21.

The liquid serving for the wet-treatment of the goods A wound upon the spool may be forced through the goods by pressure or 80 suction action. In the first case the liquid under pressure is supplied by means of the conduit 18, to the interior of the spool from where it passes through the goods and flows off through the conduit, 20. In the second 85 case the liquid is placed in the receptacle 12, from which it is sucked through the wound-up goods A by the pump 21, and is discharged by the conduit, 23.

What I claim is:

1. As an improvement in the treatment of 90 textile threads, a method which includes the steps of winding the threads upon a hollow holder then relaxing the threads while on the holder, and then causing flow of liquid 95 through the goods between the exterior and the interior of the holder.

2. As an improvement in the treatment of 100 textile threads, a method which includes the steps of winding the threads upon a hollow 100 holder then relaxing the threads while on the holder, and then causing flow of liquid through the goods between the exterior and the interior of the holder, the flow of liquid taking place only within the limits of the 105 thread on the spool.

3. As an improvement in the treatment of 110 textile threads, a method which includes winding threads upon a hollow holder, then reducing the diameter of the holder to relax 110 the threads thereon while maintaining a tension of the threads that will retain their position on the holder and then with the ends of the holder closed to prevent liquid flow other than through the body of threads on the exterior of the holder, causing the flow of liquid 115 through the body of threads between the inside and outside of the holder.

4. As an improvement in the treatment of 120 textile threads, apparatus for the wet-treatment thereof, comprising a hollow spool having means for permitting liquid flow between the exterior and interior of the spool and having movable thread-engaging circumferential portions, said portions when moved 125 inward substantially closing the spool circumference to the passage of liquid beyond the thread-encircling portions of the spool.

5. As an improvement in the treatment of textile threads, apparatus for the wet-treatment thereof, comprising a hollow spool having means for permitting liquid flow between the exterior and interior of the spool and having radially movable convex thread receiving portions and stationary portions towards

and from which said movable portions are movable and with which they contact when moved inward whereby liquid flow at the 10 places of contact is prevented.

In testimony whereof I hereunto affix my signature.

MORRIS SCHOENFELD.
